FIG. 4

FIG. 1

FIG. 2

FIG. 3

FIG. 5

FIGURE 1 is a perspective view of a combined receiver and warning signal showing my new design;

FIGURE 2 is a front elevational view;

FIGURE 3 is a side elevational view, the opposite side being substantially a mirror image thereof;

FIGURE 4 is a top plan view; and

FIGURE 5 is a bottom plan view.

The dominant features of my design reside in the portions shown in full lines.

The rear is substantially flat and unornamented.

I claim:

The ornamental design for a combined receiver and warning signal, as shown and described.
